UNITED STATES PATENT OFFICE.

ROBERT E. KELLOGG, OF MADISON, WISCONSIN.

TRACTOR.

1,288,022.

Specification of Letters Patent. Patented Dec. 17, 1918.

Application filed May 12, 1916. Serial No. 97,108.

To all whom it may concern:

Be it known that I, ROBERT E. KELLOGG, a citizen of the United States, residing at Madison, in the county of Dane and State 5 of Wisconsin, have invented certain new and useful Improvements in Tractors; and I do hereby declare the following to be a full, clear, and exact description of the invention, such as will enable others skilled in the art 10 to which it appertains to make and use the same.

This invention relates to new and useful improvements in tractors and more particularly to that type in which an internal combustion engine is used as the motive power. It is to be understood however that any suitable type of motive power may be used in connection with this invention without departing from the spirit and scope of the 20 same.

Another object of the invention is to provide a tractor having a low center of gravity thereby increasing the effectiveness of the device and reducing the possibility of overturning to a minimum thus increasing the utility of the device and allowing the use 25 of the same on hillsides.

A still further object of the invention resides in the provision of a simple means for controlling the movement of the device and steering the same in various directions.

A further and more specific object of the invention is the provision of a tractor in which the speed of its movement may be 30 easily controlled and varied to suit varying conditions.

Still another object of the invention resides in the provision of a tractor eliminating the use of driving chains reducing the 40 friction to a minimum, thereby reducing the wear.

A further object of the invention resides in the reduction of the steering radius of such devices thus permitting the device to 45 make a shorter turn.

With these and other objects in view, the invention consists in the novel combination and arrangement of parts which will be 50 fully set forth in the following specification and accompanying drawings, in which:—

Figure 1 is a vertical sectional view of a tractor constructed in accordance with this invention.

Fig. 2 is a top plan view of the same.

Fig. 3 is an enlarged detail sectional view 55 of the front construction of the device.

Fig. 4 is a detail sectional view of the rear construction of the device.

Fig. 5 is an enlarged detail sectional view 60 through the clutch, and

Fig. 6 is an enlarged transverse fragmentary sectional view through the front construction taken at right angles to Fig. 3.

Referring to the drawings 1 designates the main frame of the device comprising a pair 65 of side bars 2 connected at the forward ends by a transversely extending cross bar 3. A cross bar 4 is positioned inwardly from the extreme rear terminals of the side bars 2 as clearly illustrated in the drawings. Mounted 70 transversely on the frame and spaced inwardly a short distance from the cross bar 3 is a transversely extending cross bar 5 the use of which will appear as the description proceeds. The engine frame is designated 75 generally by the numeral 6 and comprises a pair of side bars 7 which are joined at their forward ends by the cross bar 8 as clearly shown in Fig. 2 of the drawings. The engine frame above referred to is suspended 80 below the main frame 1 by the vertical hanger bars 9 and extends rearwardly beyond the rearmost terminal of the main frame to provide a platform support. A suitable bow 10 extends between the foremost hanger bars 9 as clearly illustrated in 85 the drawings and this body portion is positioned at a point in a plane with the forward portion of the bar 8.

Formed centrally of the cross bar 4 is a 90 suitable bearing in which the main drive shaft 11 is journaled and the forward end of this drive shaft is journaled in a suitable bearing formed on the yoke in which the forward construction is mounted. Secured 95 to the shaft 11 near its rear end is the bevel gear 12, and journaled on the shaft 11 in spaced relation to the gear 12 is a gear 13— 13 and said gears mesh with the pinions 14 carried on the bosses 15 of the main drive 100 gear designated generally by the numeral 16. This drive gear 16 is provided with a pair of gear faces 17 and 18 which in turn are adapted to mesh with suitable shifting gears mounted on the motor shaft as will be more 105 fully hereinafter described. Formed integral with and extending rearwardly from the gear 13 is a bevel pinion 19 the use of which will appear as the description proceeds.

Secured to the rearmost vertical hanger bars 9 and on the rear faces thereof are the 110

bearing blocks 20 in which the rear axle 21 is journaled and secured to opposite ends of the rear axle are the hubs 22 of the rear wheels designated generally by the numeral 23. Radiating from the hubs are the spokes 24 to which are secured at their outer ends the rims 25. Keyed or otherwise secured to the axle 21 is a spur gear 26 which meshes with a pinion 27 mounted on the shaft 28 which is journaled in suitable bearings at the rear ends of the side bars 2 of the frame 1. A suitable bevel gear 29 is keyed or otherwise secured to the shaft 28 and meshes with the bevel pinion 19 so that upon the rotation 15 of the gear 18 the rear wheels will be driven.

The forward wheel construction is rotatably mounted with relation to the frame 1 by means of a suitable yoke designated by the numeral 30 which comprises a body 31 formed on its under side with an inverted cup 32 and on its upper side with a pair of forwardly and rearwardly extending arms 33. The foremost arm is riveted as at 34 to the bar 3 of the frame 1 while the rearmost arm is formed with a bearing 35 which is riveted to the bar 5 and in which the forward end of the shaft 11 is journaled. A bevel pinion 36 is mounted on the forward end of the shaft and adapted to rotate therewith 30 and this pinion meshes with the bevel gear 37 mounted on the upper end of the stub shaft 38 which is rotatably mounted in a bore 39 which extends through the body 31. The lower end of this stub shaft carries one 35 section 40 of a suitable universal joint which is clearly shown in the drawings. A flange 41 is formed on the lower edge of the cup 32 thereby forming an enlarged chamber below the hollow portion of the cup and rigidly 40 secured to the lower terminal of the flange 41 is a ring 42 which extends inwardly and partially incloses the cup.

The front axle of the device is designated generally by the numeral 43 and consists of a 45 tubular body 44 formed with a central enlargement 45 which is hollow and forms the chamber 46 in which the differential gearing which will be more fully hereinafter described is mounted. A hollow stem 47 extends upwardly from the enlargement 45 and is provided near its upper end with ears 48 which are pivotally mounted with the ring 49 which is rotatably mounted within the chamber formed by the flange 41 on the 50 cup 32. An enlarged axially extending chamber is formed between the ears at the upper end of the stem and receives the lower section 50 of the universal joint previously referred to. Extending through the hollow 55 stem 47 is a shaft 51 to which the lower section 50 of the universal joint is connected and the lower end of this shaft carries the bevel pinion 52 which is adapted to drive the differential contained within the chamber 60 46. It will be seen upon reference to Fig. 6

that the front axle is rockably mounted on the pin 49 which extends through the ears and into the ring so that in going over rough places the front axle may rock to prevent any breakage of the frame or straining of 70 the parts.

The last named differential comprises a housing or casing 53 which is rotatably mounted within the chamber 46 and has one end open for closure by the plate 54 formed 75 with an annular flange having an annular series of bevel teeth 55 which are adapted to mesh with a pinion 52. Secured to and extending inwardly from the circular wall of the casing 53 are the studs 56 on which the 80 bevel pinions 57 are mounted and these pinions 57 mesh with pinions 58 and 59 which are connected for rotation with the drive axles 60 and 61 respectively. These drive axles 60 and 61 are rotatably mounted on 85 suitable bearings within the tubular casing 44 and project beyond opposite ends of said casing to receive the hubs 62 of the front tractor wheels designated generally by the numeral 63. These hubs have radiated therefrom 90 the spokes 64 and secured to the outer ends of the spokes as clearly shown in the drawings are the rims 65.

Extending downwardly from the under side of the enlargement 45 and at a point 95 centrally of the axle 43 is a stud 66 around which the eye 67 of the brace rod 68 extends. This rod 68 extends upwardly and rearwardly from the stud 66 and into a socket 69 formed in the steering head which will be 100 more fully hereinafter described. A pair of angularly extending brace rods 70 are connected to suitable lugs 71 formed at opposite ends of the axle 43 and converge toward the socket 69 and are secured to the brace rod 105 68 previously referred to. The bearing head previously referred to is designated generally by the numeral 72 and comprises a body 73 having the axial opening or socket 69 formed therein which communicates at its 110 inner end with the chamber 74 which in turn communicates at its rear end in an enlarged chamber 75. A vertical bore 76 extends through the head 72 and has rotatably mounted therein the shaft 77 carrying at its 115 upper end the worm gear 78 which meshes with the worm 79 on the shaft 80. The forward end of the shaft 80 is rotatably mounted in the yoke 81 which is in turn swivelly mounted in a manner which will be 120 more fully hereinafter described. Secured in the head 72 and extending into the chamber 75 are suitable studs 82 on which the rollers 83 are rotatably mounted.

Extending forwardly from the center of 125 the bow 10 is a suitable bracket 84 which supports a toothed sector designated generally by the numeral 85, the inner face of which is provided with a plurality of gear teeth 86 which are adapted to mesh with the 130

pinion 87 secured to the shaft 76 within the chamber 74. The sector 85 is provided with a pair of upwardly extending flanges 88 on opposite side edges and these flanges are 5 adapted to form guideways on which the rollers 83 travel.

In order to further assist the tractor 84 in the support of the sector 85 a pair of arms 89 are provided and are secured to the bow 10 10 at the point intermediate its upper and lower edges. Suitable brace arms 90 extend forwardly from the foremost vertical bars 9 and are also secured to the sector 85 at its outer ends. In order to further assist in the 15 support of the forward ends of the sector 85 brace arms 91 are secured thereto and are connected at their opposite ends to the side bars of the frame.

In order to control the movement of the 20 pinion 87 a pair of bevel gears 92 and 93 are loosely mounted on the shaft 11 near its forward end and are provided with inwardly disposed clutch faces which are adapted to be engaged by the clutch member 94 which is 25 splined to said shaft. It will thus be seen that upon the movement of the clutch 94 into engagement with either of the gears 92 or 93 one or the other of the gears will be rotated in the direction of the rotation of the shaft. 30 A bracket 95 is secured to the bar 5 and mounted in said bracket is a shaft 96 the upper end of which has secured thereto a bevel pinion 97 which meshes with pinions 92 and 93 and is adapted to be driven thereby. The 35 lower end of this shaft projects through the yoke 81 and mounted within the yoke and secured to the shaft is a suitable worm 98 which meshes with the worm gear 99 at the forward end of the shaft 80. It will thus be seen that 40 upon movement of the clutch 94 into engagement with either of the pinions 92 or 93 the shaft 96 will be rotated thereby imparting rotation to the shaft 80 and causing the worm gear 78 to rotate thus rotating the shaft 76 and causing the pinion 87 to 45 travel along the sector 85 in a direction which is governed by the direction of rotation of the shaft 96. In this way it will be noted that the movement of the pinion 87 50 will cause the steering head to travel thereby causing the axle 43 to assume various positions with relation to the longitudinal axis of the vehicle.

In order to provide a motive power for 55 controlling the operation of the device a suitable internal combustion engine 100 is provided and is mounted in the frame 6. The drive shaft 101 of said engine carries a clutch member 102 in connection with which 60 the coöoperating clutch member 103 operates. This clutch member 103 is secured to the transmission shaft 104 on which is splined a sleeve 105 carrying at one end a pinion 106 which is adapted to mesh with the gear face 65 17 of the gear 16 when the device is travel-

ing at low speed. The opposite end of the sleeve is provided with a pinion 107 which is adapted to mesh with the gear face 18 of the gear 16 when the device is traveling at an increased rate of speed. In this way it 70 will be seen that the speed of the tractor may be varied to suit varying conditions and the steering of the device is automatically accomplished by mere shifting of the clutch member 94 into either of its operative positions. 75

While in the foregoing there has been shown and described the preferred embodiment of this invention, it is to be understood that such changes may be made in the combination and arrangement of parts as will fall within the spirit and scope of the appended claims. 80

What is claimed is:—

1. A tractor comprising a frame, a driven shaft on said frame, means driving said shaft, a rear axle on said frame, means connecting said shaft with the axle, a body secured to said frame and having an inverted cup in its lower end, a ring rotatably mounted within said cup, a housing, a front axle in said housing, an enlarged portion formed on said housing, a differential connected to the front axle and located within the enlarged portion, a hollow stem formed on 85 said enlarged portion and pivoted to the ring, a stub shaft journaled in said body, means connecting said stub shaft to the driven shaft, a universal joint connected to the stub shaft and located within the cup 90 and the hollow stem, and means connecting the universal joint with the differential. 95

2. A tractor comprising a frame, a driven shaft on said frame, means driving said shaft, a rear axle on said frame, means connecting said shaft with the rear axle, a body secured to said frame and having an inverted cup in its lower end, a ring rotatably mounted within said cup, a retaining ring 105 secured to the periphery of the cup and partially closing the same to hold the first named ring against displacement, a housing, a front axle journaled in said housing, an enlarged portion formed on said housing, a differential secured to the front axle and located within the enlarged portion, a hollow stem formed on the enlarged portion and pivoted to the first named ring, a stub shaft 110 journaled in the body and connected to the driven shaft, a universal joint connected to the stub shaft and located within the cup and hollow stem, and means connecting the universal joint with the differential. 115

3. A tractor comprising a frame, a driven shaft on said frame, means driving said 125 shaft, a rear axle on said frame, means connecting said shaft with the axle, a body secured to said frame and having an inverted cup in its lower end, a ring rotatably mounted within said cup, a housing, a front axle 130

journalized in said housing, an enlarged portion formed on said housing, a differential secured to the front axle and located within the enlarged portion, a hollow stem formed on said housing, ears formed on said stem and pivoted to the ring, a stub shaft journalized in the body and connected to the driven shaft, a universal joint connected to the stub shaft and located within the cup and hollow stem, a second stub shaft jour-

naled in the hollow stem and connected to the universal joint, and means connecting the second stub shaft to the differential.

In testimony whereof I affix my signature in presence of two witnesses.

ROBERT E. KELLOGG.
